ABSTRACT OF THE DISCLOSURE

In a standard rocker type "on-off" switch, a switch lever is provided which is asymmetrical with respect to the pivot axis, with an accessible projection in the direction of the "off" position greater than in the direction of the "on" position with respect to the pivot axis, so that the switch is most readily moved to the "on" position by grasping sides and lifting up of the projection of the lever in the "off" direction, a relatively difficult manipulation, and is readily moved to the "off" position by pressure against the lever.

BACKGROUND OF THE INVENTION

In conventional rocker switches of the type used on radial saws, bench saws, drill presses and the like, an "off-on" lever is provided which is symmetrical with respect to the pivot axis in its accessible areas, and is moved to the "on" and "off" positions with equal effort. The shape of the lever is such as to make it necessary as a practical matter to turn the switch to either position with one's thumb or finger.

One of the objects of this invention is to provide a switch which is easy to turn off and relatively difficult to turn on.

Other objects will become apparent to those skilled in the art in the light of the following description and accompanying drawings.

SUMMARY OF THE INVENTION

In accordance with this invention, generally stated, in an "on-off" switch wherein a manually operated switch lever is pivoted on an axis for rocking or rotating movement between "on" and "off" position, a switch lever is provided which is asymmetrical with respect to the pivot axis, with an accessible projection in the direction of the "off" position greater than in the direction of the "on" position with respect to the pivot axis.

The invention has particular application to a rocker switch with a rectangular housing on which a lever is mounted for rocking movement between two mounting brackets which normally define the limits of accessibility of the lever. In the switch of this invention, the "on" end of the lever slopes to an edge inboard of a mounting bracket while the "off" section of the lever projects over the other bracket in the "off" position and is arranged to clear a hole in the mounting bracket in the "on" position.

BRIEF DESCRIPTION OF THE DRAWINGS

In the drawing, FIG. 1 is a view in side elevation, with interior parts shown in dotted lines, of one illustrative embodiment of the sketch of this invention; and

FIG. 2 is a sectional view taken along the line 2—2 of FIG. 1.

DESCRIPTION OF THE PREFERRED EMBODIMENT

Referring now to the drawing for one illustrative embodiment of safety switch of this invention, reference numeral 1 indicates a completed switch, having a rec-

2

tangular housing 2, a pivot frame 3, mounted on the housing 2, a pivot pin 4 mounted on the frame 3, and an "on-off" lever 5 rockably mounted on pivot pin 4.

The housing 2 has a long narrow bottom wall 21, two broad side walls 22, two short narrow end walls 23 and a long narrow open mouth 24 defined by a planar edge 25. Terminal ears 26, projecting from the bottom wall 21, form part of electrical components 27 which, while essential elements of the electric switch, form no part of this invention. The housing 2 and its contents are in all respects conventional.

The pivot frame 3 is also conventional. It is symmetrical with respect to the housing and is made of a one piece stamping which includes mounting clamps 31 crimped under shoulders provided on the housing; a pair of flange members 32 embracing the upper edge of the long side walls; two mounting brackets 33, with a riser part 34 projecting substantially parallel to and beyond the end walls 23, and a ledge part 35 with a hole 36 in it to receive a mounting screw, and two pivot plates 36.

The pivot pin 4 is mounted centrally, between the two mounting brackets 33. The pin 4 has a head 41 at each end. Both the frame 3 and the pin 4 are conventional.

The lever 5 is constructed conventionally in the area between the pivot pin 4 and the bottom of the casing, and includes a grooved semi-circular body 51, bosses 52, integral with the body, and spring loaded plungers 53, which serve to actuate the electrical elements of the switch. Integral with the body portion 51 beyond the outer edge of the pivot plates 36, the lever is formed with a sloped "on" section 55, which, in the embodiment shown, is curved on a radius with the pivot axis, and an "off" section 56. The "off" section 56 has a part 57 projecting, in the "off" position as shown in solid lines in FIG. 1, over the bracket ledge 35.

In the embodiment shown, both the "on" and "off" sections of the lever have a top surface 60 of substantial width, and two side surfaces 61. An end surface 62 at the "off" end of the lever, slopes from the top surface of the "off" section part at a re-entrant angle toward the housing. As shown particularly in FIG. 1, in the "off" position of the lever, the end surface 62 projects from the outer edge of the ledge 35 sufficiently to provide a lifting surface so that the lever can be moved to "on" position if the bracket ledge 35 is flush with a road surface by manually pushing up on the end surface 62. The angle of the end surface 62, however, is so related to the throw of the switch as to clear the mounting hole in ledge 35 when the lever is in the "on" position, as indicated in broken lines in FIG. 1.

In the embodiment shown, an end edge 65 at the "on" end of the lever surfaces has a stop shoulder 66, abutting an upper surface of the frame 3 when the switch is in the "on" position.

It can be seen that, because of the slope of the lever surface in the "on" section of the lever, it is very difficult to rock the lever to the "on" position merely by pressing the lever on the "on" side of the pivot. It is easier to grasp the side of the lever on the "off" side or to push on the surface 62. On the other hand, it is very easy to rock the lever from "on" to "off" position by pushing on the top surface 60 of the projecting section of the lever on the "off" side. Thus, the switch can be rocked to the "off" position by brushing it with one's knee or elbow, or almost any other part of the body, if his hands are occupied.

Numerous variations in the construction of the switch of this invention, within the scope of the appended claims, will occur to those skilled in the art in the light of the foregoing disclosure. Merely by way of example, the

sloped surface of the "on" section of the lever might be made planar instead of arcuate, as long as the slope is such as to inhibit turning the switch on by pressing on that section. This is merely illustrative.

Having thus described the invention, what is claimed and desired to be secured by Letters Patent is:

1. In an "on"-off switch having a switch housing and a manually operated switch lever pivotally mounted on said housing for rocking movement between "on" and "off" positions, the improvement comprising a switch lever asymmetrical with respect to the axis on which it is pivoted, said switch lever having a top surface including an "off" section on one side of said pivot axis and an "on" section on the other side of said pivot axis, exposed to manipulation through a reach from said "off" section to said "on" section, said "off" section having greater accessible projection than said "on" section with respect to the pivot axis, said "off" section moving away from said housing in moving from "off" to "on" position and toward said housing in moving from "on" to "off" position, and said pivot axis lying between the top surface of the "off" section and the housing, whereby said switch is turned off more easily than it is turned on.

2. The improvement of claim 1 wherein the part of the lever on the "off" side of the pivot axis has graspable side surfaces, whereby the lever can be pulled to rock it to "on" position.

3. In a rocker switch of the type having a rectangular housing with a long narrow bottom wall, two broad side walls, two short narrow end walls and a long narrow open mouth defined by a planar edge, in which an operating lever is mounted for rocking movement between an "off" position toward one end wall and an "on" position toward the other end wall on a pivot pin mounted centrally with respect to the narrow end walls on said housing across and spaced outwardly from the mouth of said housing and two mounting brackets on said housing, one at each short narrow end wall of the housing, having a riser part extending beyond the mouth of the housing and defining lateral limits of accessibility for manipulation of said lever, said bracket having ledge parts projecting in a direction outboard from the housing and each having a hole therein for the reception of mounting means, the improvement comprising said lever's having a top surface, two side surfaces and at least one end surface, a convexly rounded section between a plane including the axis of the pivot pin and perpendicular to the plane of the edge defining the open mouth of the housing and a part of the lever adjacent the one of the brackets on the "on" end wall of the housing, said lever part being inboard of and within the outermost reach of the said bracket when the lever is in "on" position and said lever having a second section between said plane and the other of said brackets, said second section projecting toward and over the ledge of the said other bracket, said section having an end surface sloped from the top surface of said section at a reentrant angle toward the housing whereby when the lever is in its "on" position, the said end surface is inboard of the mounting means receiving hole in the ledge of the bracket, and is farther from the said ledge than it is in its "off" position.

4. The improvement of claim 3 wherein the distance from the axis to the top surface on the "off" side of the plane through the axis is greater than the distance from the axis to the top surface at every point on the "on" side of the plane through the axis in both "on" and "off" positions of the lever.

5. In an "on"-off switch having a switch housing and a manually operated switch lever pivotally mounted on said housing for rocking movement between "on" and "off" positions, the improvement comprising a switch lever asymmetrical with respect to the axis on which it

is pivoted, said switch lever having a top surface including an "off" section on one side of said pivot axis and an "on" section on the other side of said pivot axis, exposed to manipulation through a reach from said "off" section to said "on" section, said "off" section having greater accessible projection than said "on" section with respect to the pivot axis, said "off" section moving away from said housing in moving from "off" to "on" position and toward said housing in moving from "on" to "off" position, and said pivot axis lying between the top surface of the "off" section and the housing, whereby said switch is turned off more easily than it is turned on, said "on" section being sloped from the area of the axis toward the housing to inhibit moving the switch to "on" position by pressing on the said part.

6. In an "on"-off switch having a switch housing and a manually operated switch lever pivotally mounted on said housing for rocking movement between "on" and "off" positions, the improvement comprising a switch lever asymmetrical with respect to the axis on which it is pivoted, said switch lever having a top surface including an "off" section on one side of said pivot axis and an "on" section on the other side of said pivot axis, exposed to manipulation through a reach from said "off" section to said "on" section, said "off" section having greater accessible projection than said "on" section with respect to the pivot axis, said "off" section moving away from said housing in moving from "off" to "on" position and toward said housing in moving from "on" to "off" position, and said pivot axis lying between the top surface of the "off" section and the housing, whereby said switch is turned off more easily than it is turned on, said "off" section having a reentrant end surface of sufficient extent to permit its being pushed by human finger from "off" to "on" position.

7. In an "on"-off switch having a switch housing and a manually operated switch lever pivotally mounted on said housing for rocking movement between "on" and "off" positions, the improvement comprising a switch lever asymmetrical with respect to the axis on which it is pivoted, said switch lever having a top surface including an "off" section on one side of said pivot axis and an "on" section on the other side of said pivot axis, exposed to manipulation through a reach from said "off" section to said "on" section, said "off" section having greater accessible projection than said "on" section with respect to the pivot axis, said "off" section moving away from said housing in moving from "off" to "on" position and toward said housing in moving from "on" to "off" position, and said pivot axis lying between the top surface of the "off" section and the housing, whereby said switch is turned off more easily than it is turned on, said "on" section of the pivot axis being sloped from the area of the axis toward the switch on a radius with the pivot axis to inhibit moving the switch to "on" position by pressing upon the said part.
